TEMPERATURE CONTROLLED VALVE

James Pymm, Brooklyn, N. Y.

Application February 21, 1933, Serial No. 657,772

1 Claim. (Cl. 158—117.1)

This invention relates to safety valves for controlling the flow of fluids in gas mains, ranges, radiators and water heaters, sprinkler heads, pipes and cut-off boxes on water mains or in any other situation where it is desired to control the flow of gas, water or other fluid upon the happening of some event which changes the temperature in the vicinity of the valve.

The principal object of the invention is a simple and reliable device for automatically controlling the flow of gases or liquids in accordance with temperature changes.

Another object of the invention is an inexpensive device of the type referred to which may be manufactured and sold as a unit and may be attached to existing mains, ranges and other appliances without altering the construction of the appliance itself.

Another object of the invention is an improved device for regulating the flow of gas to a burner and for automatically shutting off the gas when the flame is accidentally extinguished.

I shall describe the invention in its application to gas burners where it functions to shut off the gas when the flame is extinguished but as the description proceeds it will be evident that the device may be used equally well in sprinkler heads, etc. to turn on water or other fluid when the temperature rises sharply due to fires or other causes.

Wherever gas is used for heating or lighting purposes there is danger of gas escaping and causing injury to health, or death by asphyxiation, as well as property damage from explosions.

This sometimes results from a flame being blown out, or a gas cock being turned on by a child, and is sometimes caused by failure of the gas supply which puts the flame out and then allows the gas to escape without being ignited when the supply is turned on again. In most communities, when the gas supply fails, it is customary to despatch messengers to warn housewives and other gas users to turn off all gas cocks before the supply is cut in again. This entails considerable trouble and expense and does not always prevent disaster when the occupants of a house are out or asleep when the messenger calls.

I avoid the above hazards and inconveniences by providing a simple and reliable control device which may be attached to any gas burner and is adapted to control the flow of gas and to shut it off automatically when the flame is extinguished from any cause whatever. My device employs an element which is responsive to changes in temperature and is arranged to actuate a valve

or plurality of valves controlling the supply of gas to a burner and is supplementary to the usual hand control. The heat-responsive element is preferably a flexible metal cone or bellows diaphragm which expands when heated and contracts to normal size when cooled. When expanded by the heat of a burner or pilot flame the diaphragm holds the gas valve or valves open and when the burner or pilot flame goes out the diaphragm contracts and closes the valve or valves and shuts off the flow of gas to the burner.

My invention is capable of various modifications and adaptations as will appear from the following description. In some cases the diaphragm is heated directly by the flame from the burner head and hence will be expanded only when the gas is lighted at the burner head. In such case the gas valves are opened by a hand control in order to ignite the gas at the burner head and as soon as the diaphragm is expanded by the heat, which will be in a few seconds, it will hold the valves open until they are turned off by operation of the hand control or by automatic contraction of the diaphragm if the flame is accidentally extinguished. If the gas is turned on by hand without being ignited at the burner head, as may sometimes be done by a child or accidentally by a housewife, the diaphragm will not be heated and it will therefore close the valves the instant the hand control is released. This device may be used with one or more valves, depending upon the situation in which it is used, a plurality of valves increasing the safety factor by shutting off the gas at two or more different points.

The above and other features and advantages of the invention will be described in connection with the accompanying drawing, in which:

Fig. 1 is a longitudinal section through a gas burner embodying the invention;

Fig. 2 is a plan view with parts of the shank broken away to show the interior;

Fig. 3 is a front view of the range or other casing showing the single control knob; and

Fig. 4 is a detail view of the valve actuating mechanism.

For purposes of illustration the burner is mounted in a gas range having top plate 1 and front plate 2 containing gas main 3 although it may be used in any other kind of gas appliance, main, pipe, etc.

The burner itself may be of any suitable construction such as the well known type having burner head 4, shank 5 and butterfly valve 6 disposed in a passage in valve chamber or pipe 7 which connects the shank to gas main 3.

The inner end of pipe 7 is provided with a needle or plunger valve comprising valve seat 8 formed in the pipe and cooperating plunger 9 which is adapted to slide in a guide frame 10 secured to pipe 7 as by screws 12.

Valve plunger 9 is mounted on one end of rod 13 which extends lengthwise through shank 5. The other end of this rod is secured to inner end 14 of a movable frame 15 disposed in casing 16 which is connected to shank 5 by threaded bushing 17. Casing 16 is open at the top to receive heat through the central opening in burner head 4. Coil spring 18 surrounds rod 13 and is compressed between plunger 9 and bushing 17.

15 Stationary bar 19 extends through frame 15 and is secured to the wall of casing 16 in any suitable manner. Frame 15 contains a thin gas-tight metal cone or bellows diaphragm 20 containing ether or any other suitable gas which 20 will cause the diaphragm to expand like an accordion when heated and to contract to normal size when cooled. One face of diaphragm 20 is attached to the outer end of movable frame 15 while the other face is secured to stationary bar 19. When diaphragm 20 is contracted plunger 9 is seated in valve seat 8 and hence gas cannot enter shank 5. When diaphragm 20 expands, due to heating, it exerts pressure on bar 19 and on the outer end of frame 15 and, since bar 19 is stationary, the expanding diaphragm moves frame 15 outwardly to the limiting expanded position shown in Fig. 1.

Movement of frame 15 causes a corresponding movement of plunger rod 13 which is secured to the inner end of frame 15. Hence movement of frame 15 and plunger rod 13, due to expansion of diaphragm 20, causes plunger 9 to move off seat 8 into the dotted line position shown in Figs. 1 and 2 in which position gas will flow into shank 5 inasmuch as butterfly valve 6 is also opened at the same time as hereinafter described. When diaphragm 20 contracts it returns frame 15, rod 13 and plunger 9 to the position shown in full lines in Figs. 1 and 2, thus closing the plunger-operated valve. The automatic operation of these parts will be described later.

50 Butterfly valve 6 and plunger valve 9 are operated by control rod 21 which slides in a longitudinal direction. The outer end of this rod carries an actuating knob 22 and a series of ratchet teeth 23 adapted to engage the edge of slot 24 which is formed in front plate 2 of the range. The inner end of rod 21 is pivotally connected by pin 25 to pivot arm 26 the center of which is secured to pivot pin 27 carrying butterfly 6. The other end of arm 26 is pivoted by pin 28 to the lower end of an elongated track or sleeve 29 as shown in Figs. 1 and 4. Valve plunger 9 carries elbow 30 which slides in sleeve 29. Hence longitudinal movement of control rod 21 turns pivot arm 26 which rotates pivot pin 27 and butterfly 6 and also moves sleeve 29 in a direction opposite to that of control rod 21.

65 When the parts are in the position shown in Figs. 1, 2 and 4 butterfly valve 6 and plunger valve 9 are both closed and hence the gas is shut off. Now, in order to light the gas, knob 22 is raised as viewed in Figs. 2 and 3 (or moved to the left as viewed in Fig. 1) to disengage ratchet 70 23 from the edge of slot 24 and is then pulled out any desired distance depending upon the flow of gas required. When the gas has been ignited ratchet 23 is again moved into engagement with the edge of slot 24 to hold control rod 21 in adjusted position. When control rod 21 is pulled

5 out in this manner it turns pivot arm 26 which rotates pivot pin 27 and thereby turns butterfly 6 to the open position shown in dotted lines in Fig. 1. Pivot arm 26 also pushes sleeve 29 back toward the burner head, carrying with it elbow 30 and thereby moving plunger 9 off valve seat 8. Gas now flows from main 3 through pipe 7, butterfly valve 6, plunger valve seat 8 and shank 5 to burner head 4 where it is ignited in the usual manner.

10 The heat from the flame impinges on diaphragm casing 16 and heats up diaphragm 20 which moves to the expanded position in Fig. 1 as previously described. In so expanding, diaphragm 20 moves frame 15 outwardly and thereby moves plunger rod 13, plunger 9 and elbow 30 to the position shown in dotted lines in Fig. 1 and holds them in such position as long as the gas is burning. If the gas is accidentally extinguished from any cause whatever, diaphragm 20 will quickly cool and contract thereby returning frame 15 to its original position and returning plunger rod 13, plunger 9 and elbow 30 to the position shown in full lines in Fig. 1. Plunger 9 thus returns to valve seat 8 and thereby shuts off the flow of gas at this point. At the same time elbow 30 slides into sleeve 29 and, when it reaches the end of said sleeve, elbow 30 carries the sleeve with it and thereby rotates pivot arm 26 in a direction to close butterfly 6 thus shutting off the flow of gas at this point. Such rotation of pivot arm 26 also draws control rod 21 back to the "off" position shown in full lines in Figs. 1 and 2, ratchet teeth 23 being tapered in a direction such that they will ride off the edge of slot 24 when control rod 21 is pulled toward the burner head but will lock the rod securely against any force or accidental jars tending to move it to an "open" position away from the burner head.

40 The flame may of course be extinguished by grasping knob 22 and pushing control rod 21 back toward shank 5 to the limiting "closed" position shown in full lines in Figs. 1 and 2. Rod 21 thereby turns pivot arm 26 in a direction to close butterfly 6, shutting off the flow of gas at this point. Pivot arm 26 also moves sleeve 29 outwardly toward front plate 2 of the range but does not move elbow 30 which for the time being remains in the dotted line position shown in Fig. 1 inasmuch as plunger 9 is still held open due to 50 the fact that diaphragm 20 is still expanded. The flow of gas, however, is now shut off by butterfly 6 and, as soon as the flame is extinguished, diaphragm 20 cools and contracts and plunger 9 returns to its valve seat 8 as previously described. Elbow 30 also returns to its limiting position inside sleeve 29 ready to be moved with said sleeve when control rod 21 is again drawn out preparatory to lighting the gas as explained above. The device may be used in conjunction with an ordinary pilot light, operating as described above when the usual button is pushed to ignite the pilot flame.

55 Many changes may be made in the details of construction and method of operation described above without departing from the scope and spirit of the invention as defined in the appended claim.

60 The invention claimed is:

65 The combination with a gas burner, of a valve chamber containing a passage connecting said burner to a gas main, a rotatable valve in said chamber operable to regulate the flow of gas through said passage, a shut-off valve in said pas- 70

sage, a bellows type thermostat positioned in heating relation to said burner, a frame about said thermostat and connected to move therewith, a rod connecting said movable frame and said shut-off valve, a spring surrounding said rod tending to maintain said shut-off valve closed by tension thereagainst when said thermostat is contracted, means operatively interconnecting said valves and operable to rotate said first mentioned valve 10 and to open said shut-off valve against the tension of said spring and contracted thermostat, a

manually operable extension on said interconnecting means for manually holding said plunger valve open until said thermostat is expanded by heat from said burner, ratchet means on said extension to hold said rotatable valve in a selected open position while said shut-off valve is opened, and means responsive to the closing of said shut-off valve operable to disengage said ratchet and to close said rotatable valve.
